UNITED STATES PATENT OFFICE

2,208,476

DIE OPENING GAUGE

Gustaf S. Selander, New Britain, Conn.

Application June 1, 1939, Serial No. 276,896

1 Claim. (Cl. 33—174)

The present invention appertains to new and useful improvements in measurement instruments and more particularly to a gauge for measuring accurately the slope or angularity of openings in blanking dies.

The principal object of the present invention is to provide a gauge which in construction involves an arm which can be readily slipped into the die opening and by simply sliding the gauge along the outside of the die indication will be given on the instrument of the angularity of the wall of the opening.

Various other objects and advantages of the invention will become apparent to the reader of the following specification.

In the drawings:

Figure 1 represents a side elevational view of the gauge shown in use in conjunction with the die.

Figure 2 is a top plan view of the instrument.

Figure 3 is a vertical sectional view.

Figure 4 is a perspective view of the rocker arm.

Figure 5 is a perspective view of the lever.

Figure 6 is a perspective view of the spring unit.

Figure 7 is a front elevational view of the case with the cover plate and internal mechanism removed.

Referring to the drawings wherein like numerals designate like parts, it can be seen that the case generally referred to by numeral 5 in Figure 7, consists of the back wall 6, side walls 7—7 and the removable front wall 8. One side wall 7 is slotted downwardly at its portion as at 9 to permit the external portion of the arm 10 to extend therethrough, and this slot 9 defines the bridge piece 11 which has the beveled gauge or graduation face 12. Between the lower portion of the bridge piece 11 and the top of the front plate 8 is the space 13 through which the upper portion of the indicating arm 14 extends, this arm having its upper portion bent inwardly toward the face 12 to define the pointer tip 15.

Extending through the case 5 and through the opening 17 of the arm 10 is the pin 16.

The bottom 6 of the case has the raised boss 18 apertured to receive the screw 19 on which the arm 14 is swingable. A pin 20 extends from the pointer arm 14 and through the forked lower end of the rocker 22. The heel portion of the inverted L-shaped lever 22 has an opening 24 through which the pivot pin 23 extends, this pin being driven into the back wall 6 of the case 5.

The toe portion of the upper portion of the

lever 22 has the outstanding pin 26 (see Figure 5) which extends into the space of the yoke end of the lever 10, this space being denoted by numeral 21.

A pin 29 extends laterally from the lever 22 below the pivot pin 23 and has the upstanding leg 32 of the Y-shaped spring 31 engaging the same as shown in Figure 1.

This Y-shaped spring 31 has the trunk portion 31a anchored as at 34 and includes the additional leg 33 which is disposed upwardly and bent back downwardly as at 33a to terminate in the hook formation 33b which is engaged under the pin 20 which extends from the pointer arm 14.

In the use of the instrument the tapered end portion of the arm 10 is inserted in the opening of the die and the case of the instrument is held firmly against the outer side of the die. With a slight downward pressure of the instrument the arm will assume a rested position on the surface of the die opening. At this point the instrument is stopped and the reading taken by comparing the pointer tip 15 with the dial 12. In this manner the angularity of the opening can be readily determined.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

In a gauge for indicating the inclination of a wall of an opening in a blanking die, a casing having a flat side edge for sliding engagement with said die, a dial plate on said casing exteriorly thereof, a pointer pivoted at one end in said casing and having the other end thereof extending out of the casing alongside said dial for reading against the same, a gauge rod pivoted intermediate its ends in said casing to provide a lever arm therein and a gauge arm extending out of said side of the casing for insertion into said opening and swinging flat against said wall under sliding of said casing, and operating connections between said lever arm and said pointer comprising a bell crank lever in said casing pivoted therein and having long and short lever arms pivotally and slidably connected to said pointer and the lever arm of said rod respectively.
